Attorney

United States Patent Office.

THOMAS L. RIVERS, OF NEWARK, NEW JERSEY.

Design No. 4,933, dated May 23, 1871.

DESIGN FOR CAPS FOR TRUNK-HANDLES.

The Schedule referred to in these Letters Patent and making part of the same.

To all whom it may concern:

Be it known that I, THOMAS L. RIVERS, of Newark, in the county of Essex and State of New Jersey, have invented a new and improved Design for Caps for Trunk-Handles; and I do hereby declare that the following is a full, clear, and exact description of the same, reference being had to the accompanying drawing making a part of this specification, in which—

Figure 1 is a plan or top view of the cap as applied.

Figure 2 is a sectional view of fig. 1.

This design consists of a conical convexity, formed on the top of trunk-handle caps, so as to protect and shield the hand more fully from contact with other objects, and at the same time give a more ornamental finish to the cap.

a represents the flange of the cap.

B, the top, the sides and ends of which extend down and terminate in flange *a*, so as to form the receptacle for the head of the handle.

C is the conical convexity extending the length of top *B*, and projecting up sufficiently therefrom to pro-

tect the hand from injury when handling the trunk, as well as to give an ornamental finish to the cap.

The handle consists of a piece of leather, *D*, attached in the usual manner at each end of the trunk, the cap being placed with the receptacle formed by top *B*, over the end of the handle, and fastened, as usual, with rivets, the cap having a spur, *E*, on the interior of the receptacle, extending through a hole in the leather, for making the handle secure in its attachment to the trunk.

Having thus fully described my invention,

What I claim therein as new, and desire to secure by Letters Patent, is—

The design for caps for trunk-handles, as shown and described.

As evidence that I claim the foregoing as my invention I have hereunto set my hand and seal in the presence of two witnesses.

T. L. RIVERS. [L. S.]
